ROTARY POTENTIOMETER WITH MEANS FOR LIMITING ROTATION OF THE OPERATING SHAFT THEREOF

Joseph M. Looney, Jr., Tarzana, Calif., assignor to Acton Laboratories, Inc., Acton, Mass., a corporation of Massachusetts

Application March 3, 1959, Serial No. 796,843

3 Claims. (Cl. 338—135)

This invention relates to potentiometers and more particularly to improved means for limiting rotation of the operating shafts of rotary potentiometers.

In rotary potentiometers it is often necessary to provide stop means for limiting rotation of the operating shaft to an angle of less than 360 degrees. To be effective, the stop means must be of relatively sturdy construction. This is particularly true in trimming potentiometers where friction means are provided to apply a braking action on the operating shaft, whereby a relatively high amount of torque is required to be applied to turn the shaft to vary the setting of the slider. In such a case, it is sometimes difficult for the operator to discriminate between the drag or braking force applied to the shaft by the friction means and the resistance to rotation offered by the stop mechanism; and in his enthusiasm to rotate the shaft further, the operator may unintentionally break the stop mechanism. While making the stop mechanism stronger will obviate such an accident, it is difficult in many cases to accomplish this without making the stop mechanism larger. This is an unsatisfactory solution in the case of small precision potentiometers designed for use in airborne equipment where size and weight are critical factors.

Accordingly, the primary object of this invention is to provide a small but exceptionally sturdy stop mechanism for limiting rotation of the operating shaft of rotary potentiometers.

Other objects and many of the attendant advantages of this invention will be readily appreciated as the same becomes better understood by reference to the following detailed description when considered in connection with the accompanying drawings, wherein:

Fig. 1 is a vertical section through a potentiometer embodying the present invention;

Fig. 2 is a cross-sectional view taken along line 2—2 of Fig. 1; and

Fig. 3 is a cross-sectional view taken along line 3—3 of Fig. 1.

Referring now to Fig. 1, there is shown a rotary potentiometer comprising a cylindrical casing 2 having a removable wall 4 secured to one end thereof and a fixed wall 6 at the other end thereof. A conventional wound wire resistance element 8 extends around and is adhesively secured to the interior surface of the casing. Resistance element 8 extends through an angle slightly less than 360 degrees.

Supported by a bushing 10 which is secured by means of a force fit in a centrally located hole 12 in end wall 6 is an operating shaft 14. The inner end of shaft 14 extends into casing 2 and carries a split collar 16 which has a radially extending arm 18. Attached to the free end of arm 18 is a resilient contact member 20 which slidably engages resistance element 8. Contact member 20 is formed of electrically conductive spring metal. Although not shown, it is to be understood that casing 2 is provided with two input terminals and one output terminal, means electrically connecting the two input ter-

minals to the opposite ends of resistance element 8, a contact ring, means electrically connecting the contact ring to the input terminals, and means electrically connecting contact member 20 to the contact ring, whereby a voltage may be applied across resistance element 8 and an output voltage derived by means of contact member 20. Such elements are old as shown, for example, by U.S. Patent No. 2,778,906, issued January 22, 1957, to L. M. Burgess, and are omitted from the drawings solely to better emphasize the novel features of the present invention.

Bushing 10 consists of three integral cylindrical sections 22, 24, and 26 of different inside diameters. Bushing section 24 has the smallest inside diameter—just large enough to accommodate and rotatably support shaft 14. Bushing section 22 has an annular spacer 28 which surrounds shaft 14 and abuts against bushing section 24. Disposed within bushing section 22 are two flat spring metal elements 30 and 32. The length of spring elements 30 and 32 is greater than a chord of the circle outlined by the inner surface of bushing section 22 that is tangent to the circular outline of shaft 14. These spring elements are forced into bushing section 22 on opposite sides of shaft 14. Because of their length, these spring elements must be bent in order to fit within the bushing. The ends of these spring elements are held in tight engagement with the inner surface of bushing portion 22 by the wedging force exerted on them intermediate their ends by shaft 14. The spring elements in turn exert a clamping force on the shaft, holding it against rotation. The spring elements are held in place by an annular plug 34 which surrounds shaft 14 and is force fitted into the end of bushing portion 22. An O-ring 36 mounted on shaft 14 bears against plug 34 to prevent axial movement of the shaft away from the casing 2.

To the extent already described, the device of Fig. 1 is a high-torque potentiometer and the shaft 14 may be rotated through an angle greater than 360 degrees. The novel improvement hereinafter described functions to limit rotation of shaft 14 to an angle less than 360 degrees.

Beyond bushing portion 24, shaft 14 is of stepped construction and comprises a first or intermediate enlarged portion 40 and a second enlarged portion 42. Portion 40 has a diameter greater than the inside diameter of bushing portion 24 and smaller than the corresponding diameter of bushing portion 26. Portion 42 has a greater diameter than shaft portion 40. The latter abuts bushing section 24 to limit movement of shaft 14 toward casing 2.

The inner surface of bushing portion 26 has a semi-cylindrical groove 44 which is in alignment with and forms a continuation of a small bore 46 formed in bushing portion 24. A sturdy metal pin 48 is force fitted in bore 46 and is coextensive with groove 44. The outer surface of shaft portion 40 has a semi-cylindrical groove 50 which is in alignment with and forms an extension of a small bore 52 formed in shaft portion 42. A second sturdy metal pin 54 is seated in bore 52 and is substantially coextensive with groove 50. Pins 48 and 54 are force fitted in bores 46 and 52. Pin 48 projects inwardly and pin 54 projects outwardly by sufficient amounts to engage each other as shown in Fig. 2 when shaft 14 is rotated. It is to be noted that these stop pins make a line contact and not simply a point contact with each other. Since these pins are supported by the surrounding surfaces formed by grooves 44 and 50, they form a relatively strong stop mechanism to limit rotation of shaft 14.

It is to be noted that although grooves 44 and 50 have been described as semi-cylindrical in cross section, they may and preferably should encompass an angle slightly

greater than 180 degrees so as to offer more support to the pins 48 and 54.

A primary advantage of the stop mechanism just described is that it is simple and easy to construct and does not entail an increase in the size of the potentiometer. Another important advantage is that although the pins are relatively small in size, they offer by virtue of line contact with each other a relatively strong resistance not heretofore obtainable with the other types of mechanical stops except by the use of stop members of greater size.

Obviously, many modifications and variations of the present invention are possible in the light of the above teachings. Therefore, it is to be understood that the invention is not limited in its application to the details of construction and arrangement of parts specifically described or illustrated, and that within the scope of the appended claims, it may be practiced otherwise than as specifically described or illustrated.

I claim:

1. In a rotary potentiometer comprising a casing, an operating shaft extending into said casing, and a bushing attached to said casing having means rotatably supporting said shaft and a cylindrical portion surrounding said shaft in spaced relation therewith, the improvement comprising a first pin oriented in parallel relation to said shaft and seated throughout its length in a depression formed in said cylindrical portion of said bushing, a section of said first pin for a substantial portion of its length protruding into the space between said shaft and said cylindrical portion in exposed and spaced relation to said shaft, a second pin oriented in parallel and axially overlapping relation to said first pin, said second pin seated throughout its length in a depression formed in said shaft, a section of said second pin for a substantial portion of its length exposed to said bushing and pro-

truding into said space by an amount sufficient to engage said exposed section of said first pin when said shaft is rotated relative to said bushing.

2. The combination of a shaft having an outer cylindrical surface, a bushing having a first inner cylindrical surface surrounding and rotatably supporting said shaft and a second inner cylindrical surface spaced axially from said first surface in coaxial spaced relation with said shaft, a first pin disposed in parallel relation to said shaft and seated in an axially extending depression formed in said second cylindrical surface, a portion of said first pin protruding inwardly away from said second surface in spaced relation to said shaft, a second pin seated in an axially extending depression formed in said outer shaft surface, a portion of said second pin protruding outwardly of said outer shaft surface by an amount sufficient to make line contact with said first pin when said shaft is rotated relative to said bushing, whereby to prevent further rotation of said shaft.

3. In a potentiometer comprising a casing, a resistance element disposed in said casing, a shaft extending into said casing, and a contact element carried by said shaft in slidable contact with said resistance element, the improvement comprising a bushing attached to said casing and rotatably supporting said shaft, said bushing having a cylindrical portion in coaxial spaced relation with said shaft, a first pin mounted in a depression formed in the inner surface of said cylindrical portion and having a section thereof protruding inwardly away from said inner surface, and a second pin mounted in a depression formed in said shaft and protruding outwardly of the inner surface thereof by an amount sufficient to engage said first pin when said shaft is rotated relative to said bushing.
